UNITED STATES PATENT OFFICE.

HERBERT S. PULLMAN, OF MERIDEN, CONNECTICUT.

MACHINE FOR MANUFACTURING SHOE-LACES, &c.

SPECIFICATION forming part of Letters Patent No. 690,995, dated January 14, 1902.

Application filed May 2, 1901. Serial No. 58,470. (No model.)

To all whom it may concern:

Be it known that I, HERBERT S. PULLMAN, a citizen of the United States, and a resident of Meriden, in the county of New Haven and 5 State of Connecticut, have invented certain new and useful Improvements in Machines for Manufacturing Shoe-Laces and the Like, of which the following is a full, clear, and exact description, whereby any one skilled in the 10 art can make and use the same.

My invention relates to the manufacture of metal-tipped laces—such as shoe-laces, corset-laces, and the like; and the object of my invention is to provide an automatic machine 15 for applying the metallic tips to lacing material and then cutting the laces into proper length to leave each lace provided with a suitable metallic tip.

Referring to the drawings forming part 20 hereof, Figure 1 is a view in front elevation of a machine embodying my invention. Fig. 2 is a detail plan view of the central part of the machine, showing the mechanism by means of which the metal tip is applied to the 25 lacing. Fig. 3 is a detail view in front elevation of the ribbon-feed mechanism. Fig. 4 is a detail view in side elevation of the ribbon-feed mechanism. Fig. 5 is a detail view in cross-section, on enlarged scale, of part of the 30 ribbon-feed and mechanism for cutting the tip-blank from the end of the ribbon. Fig. 6 is a detail view, on enlarged scale in cross-section, of the tip-blank cutter. Fig. 7 is a detail view, on enlarged scale, showing the 35 lateral feed for the tip-blank. Fig. 8 is a view in side elevation of the lateral feed device and in cross-section of the closing-dies, illustrating the operation of these parts, on enlarged scale. Fig. 9 is a view in side elevation, on enlarged scale, of the lace-delivery 40 wheel. Fig. 10 is a detail view in side elevation, on enlarged scale, of the delivery-wheel and attached mechanism. Fig. 11 is a detail top view, on enlarged scale, of the cutter 45 mechanism. Fig. 12 is a detail view, on enlarged scale, of the lace-clamp device on the delivery-wheel.

In the accompanying drawings the letter *a* denotes the bed or frame of the machine, 50 which may be of any convenient size and shape, with the several mechanisms arranged

to feed a continuous length of lacing along the frame and apply to it at proper intervals the metallic tip and then sever the lacing midway of the length of the tip.

My invention is shown as embodied in a preferred form of mechanisms for the several operations, the lacing *b* being unwound from the reel *c*, as by means of the feed and press rolls *d*, mounted at one end of the frame and 55 turning at a rate of speed sufficient to maintain a supply *c'* of the lacing free and under no tension except that due to the weight of the loop. At this end of the frame the lacing passes through an automatic clamp *e*, which 60 holds it from retrograde movement, and then extends along the top of the frame to a point near the farther end, where it is held by a second clamp *e'* from any except forward movement. In effect the lacing lies along 65 the top of the frame for a space of time sufficient for the proper mechanism to cut a tip-blank from a ribbon of metal, to form it, and then close it upon the lacing. A main driving-shaft *f* is mounted in journal-bearings on 70 the frame, with a pulley *f'* at one end and connecting mechanism between the main shaft and the delivery-wheel *g*. This, as 75 shown, consists of a bevel gear-wheel *f''* on the shaft *f* in mesh with a bevel gear-wheel *f'''* fast on the upright shaft *f''*, the other end of which bears a bevel gear-wheel in mesh with a bevel gear-wheel on the driving-shaft of the delivery-wheel *g*. On the same shaft with the delivery-wheel *g* and turning with it is a 80 pulley *g'*, which is connected by a belt *g''* with a pulley *g'''* on a shaft at the right-hand end of the machine, as shown in Fig. 1, from which the feed and press rolls *d* are driven, as by 85 means of the belt *g''*.

The tip which is to reinforce the end of each lace is made from thin metal in a long strip or ribbon *h* and arranged in a roll *h'*, supported, preferably, on brackets *h''* from the carriage *i*, on which the tip-applying mechanism is mounted. This carriage is movable 90 along the bed of the machine and is adapted to be clamped in any desired position, this adjustment of the carriage being of advantage in varying the length of lace that can be made 95 on the one machine—that is, this carriage *i* may be set to make a lace of a given length,

and when it is desired to change this length the carriage is moved to a new position and clamped there.

On the shaft b a series of cam-wheels 1 2 3 4 5 are adjustably mounted, and these cam-wheels are provided with cams which operate certain mechanisms in the order in which the cams are numbered. Cam-wheel 1 (see Fig. 4) has a cam-groove k , in which a pin k' , projecting from the arm k^2 on the slide k^3 , is located. A rotary movement of the cam-wheel 1 reciprocates this slide, which is connected by the rod k^4 with an arm k^5 , mounted to swing on a rock-shaft k^6 . A pawl k^7 on the arm k^5 engages the teeth of a ratchet-wheel k^8 , which is fast to the shaft, so that the rocking movement of this arm causes the rock-shaft to turn in one direction of movement. This shaft bears the feed-roll k^9 , which is mounted to 10 coöperate with the feed-roll k^{10} as a means of feeding the ribbon h of metal toward the place where the lacing b extends across the carriage. These two feed-rolls are connected by gear-wheels k^{11} , so that their speed of rotation is the same.

The cam on the cam-wheel 1 is so shaped as to feed a desired length of the ribbon into position under a cutting-off die in a comparatively short space of time, the feed mechanism then being out of operation until the time comes for another length to be fed forward to form another tip.

A die l is located in the path of movement of the ribbon h and has a central recess l' , in which the lacing b lies. A punch l^2 is supported on the end of a lever l^3 , which is mounted to be rocked on the pivot l^4 by means of the cam-wheel 2, a pin on the lever projecting into a cam-slot in the side of the wheel. The vertical movement of this punch l^2 is sufficient to cut from the end of the ribbon a length of metal sufficient to wrap around the lacing b . A series of points are borne by the punch l^2 , and they puncture the metal of the blank and cause spurs to project from the under side of the blank, these spurs being driven into the substance of the lacing as the metal is closed about it to form the tip. As soon as the blank has been cut from the ribbon h it is moved lengthwise along the lacing b by means of a feed-slide m , on which fingers m^1 and m^2 are pivoted. This slide m is moved along a guideway in the carriage by means of a lever m^3 , which is pivoted to the carriage and is swung on its pivot by means of a cam m^4 on the side of the cam-wheel held in contact with the roller m^5 on the lever m^3 by means of the spring m^6 . This spring holds the slide in its rearward position, as illustrated in Fig. 2 of the drawings. The finger m^1 on the slide is grooved on the bottom, so that it lies closely upon the lacing b , while the finger m^2 has side parts fitting down upon the finger m^1 and forming a guide which fixes the path of the lengthwise movement of the finger m^1 with relation to the finger m^2 , the finger m^2 having its end located in a socket and

so arranged as to be held by a spring at the forward limit of its play. In Fig. 7, which may be termed the "normal" position of the parts, the finger is illustrated in connection with a blank for a tip which has been cut from the ribbon. In Fig. 8 this slide is shown at the forward end of its movement, the fingers having thrust the blank between the jaws of a closing-die, the end of the finger m^2 striking against the side of the upper die, while a shoulder on the end of the finger m^1 thrusts the blank into proper position to be operated upon by the dies. After the blank has been located in this position between the forming-dies the cam-wheel 4 in its rotation causes the upper member n of the die to slide lengthwise through the medium of the pin n' , which engages a cam-slot in the side of the cam-wheel 4. This closing-die is formed of a fixed member n^2 and a sliding member n , (see Fig. 4,) the ends of the two sections being halved together in such way that their ends overlap while leaving a space 90 between the horizontal faces, while the shoulders at the ends are curved so as to give the proper curling movement to the blank. The result of the closing movement of the dies n is to cause the metal tip to be wrapped snugly 95 about the lacing b , on which it is held by the spurs formed on the tip-blank, as well as by the compression of the blank upon the material of the lacing. It will be seen that in this operation of applying the metal tip to the lacing 100 there are four distinct operations by mechanism moved by the several cam-wheels. The ribbon is first fed forward through the medium of cam-wheel 1 and connected mechanism. A blank is then cut from the end of it 105 by means of the mechanism operated by cam-wheel 2. The blank is then fed along the lacing the desired distance by means of the cam-wheel 3 and its connected mechanism, and the blank then made to tubular form and 110 clamped upon the lacing by the mechanism operated by the cam-wheel 4. The tip now secured upon the lacing is of twice the length needed to form the end of a lace, and the next operation required is the cutting of the 115 lace at a point midway of the length of this tip. The lacing is also to be drawn along the bed of the machine, so as to present what will be the end of another lace or of two adjacent laces in proper position to receive another 120 blank to form tips.

At a suitable position, preferably the left-hand end of the machine, as shown in Fig. 1 of the drawings, a delivery-wheel g is mounted. This delivery-wheel is provided with a 125 lace-clamp o and a cutter p , these two devices being located at suitable points at or near the periphery of the delivery-wheel. The edge of the delivery-wheel g is provided on one side with a flange r , the periphery of the wheel forming a suitable surface on or in which the lacing b will lie as it is drawn from the table by the rotation of wheel g . In a suitable position near the periphery of this

delivery-wheel a clamp o is adjustably secured, the spring-arm o' being pivoted on a base o^2 and having a jaw o^3 thrust against the flange r on the wheel by means of a spring o^4 and in such manner as to firmly grasp the end of the lacing b at the proper time. This clamp is preferably mounted on the outer end of the radial arm o^5 , which is pivoted on the shaft which supports the delivery-wheel 5 and at its outer end is secured by a bolt and nut o^6 to the rim of the wheel, any desired number of openings o^7 for the reception of the bolt being provided. The cutter p is fixed on the periphery of the wheel and the clamp 10 o is made adjustable as to its distance from the cutter for the purpose of fixing the length of the lace.

In the operation of the machine the delivery-wheel g turns in the direction indicated 20 by the arrow and so as to draw the lacing b along the table or bed of the frame and onto the surface of the wheel g , the clamp o having automatically grasped the end of the lacing, which extends a short distance beyond 25 the edge of the table and upon the periphery of the wheel. A trip-arm t is secured to the frame and so located in the path of movement of the arm of the clamp and at such angle as to open the clamp-jaw as it nears the end 30 of the lacing and as the trip is cleared permit the clamp-jaw to close firmly upon and grasp the end of the lacing. If the circumference of the delivery-wheel measures seventy-two inches and the clamp is located diametrically opposite the cutter p , a lace thirty-six inches long will be cut from the lacing as the cutter p is operated by the cam p' , secured to the frame in the path of movement of the outer end of the cutter. (See Figs. 9, 35 40, 10, and 11.)

The several parts are so adjusted that the cutter p , mounted in a slideway p^2 (see Fig. 11) and held normally at the outer limit of its path by means of the lever p^3 and spring 45 p^4 , is forced inward by the cam p' and severs the lacing at or very near the center of the metallic tube that has been formed about and secured to the lacing b in the manner and by the means above described.

50 After the cutter has severed the lacing and double tip, as described, the continuous rotary movement of the delivery-wheel carries the lace which has been cut off until the clamp o is opened by the trip t' (see Figs. 9 and 10) and the lace permitted to fall into a receptacle below the wheel g .

When the double tip and the lacing have been cut, as described, the free end of the lacing lies as shown in Fig. 10 and there is no 60 tension on the lacing b except that caused by drawing it along the top of the frame and leaving it in the grasp of the friction-clamp while another piece of metal is being applied to form the tip. It follows, then, that from 65 the time when the cutter p has cut the lacing until the clamp o grasps the free end of the

continuous length there is a dwell in the forward movement of the lacing across the machine and the length of dwell incidentally varies with the length of the lace which the 70 machine is adjusted to cut.

What I claim as my invention, and desire to secure by Letters Patent, is—

1. In a machine for making laces, clamp devices for holding the lacing extended, mechanism for supplying a thin metallic blank for a tip, means for securing the tip to the extended lacing, and means for dividing the tip and severing the lacing. 75

2. In a machine for making laces, clamp devices for holding the lacing extended, mechanism for supplying a thin metallic blank for a tip, means for securing the tip to the extended lacing, means for drawing the lacing along the machine, and means for dividing 80 the tip and severing the lacing. 85

3. In a machine for making laces, a frame supporting the operative parts, means for holding a lacing extended along the frame, a delivery-wheel carrying a lace-clamp, means 90 for supplying a thin metallic blank for a tip, means for securing the tip upon the extended lacing and means for dividing the tip and severing the lacing.

4. In a machine for making laces, a frame 95 supporting the operative parts, means for holding a lacing extended along the frame, a delivery-wheel carrying a lace-clamp, means for supplying a thin metallic blank for a tip, means for securing the tip upon the extended 100 lacing and means borne by the delivery-wheel for dividing the tip and severing the lacing.

5. In a machine for making laces, a frame supporting the several mechanisms, a driving-shaft, cams mounted on the driving-shaft, a delivery-wheel mounted on the frame and in operative engagement with the driving-shaft, means for feeding a length of lacing from a roll, means for holding the lacing extended along the frame, mechanism for supplying a metallic blank for a tip, means for securing the tip upon the extended lacing, and means for automatically dividing the tip and severing the lacing. 110 115

6. In a machine for making laces in combination with means for temporarily holding the lacing extended, an adjustable carriage mounted on the frame, means for holding and feeding a ribbon of thin metal, a cutter for 120 severing a blank from the end of the ribbon, a feed device for moving the severed blank along the lacing, means for attaching the blank upon and securing it to the lacing, means for drawing the lacing along the frame, 125 and means for dividing the tip and severing the lacing.

7. In a machine for automatically applying a tip or like device to an extended cord or lacing and securing it thereto, a slide for moving the blank lengthwise along the lacing and including pivoted fingers adapted to engage 130

the edge of the blank, one of said fingers having a lengthwise movement with reference to the other finger.

8. In a machine for automatically applying a tip or like device to an extended cord or lacing and securing it thereto, a delivery-wheel with an adjustable clamp device and means for automatically grasping the end of a lacing and a cut-off device borne by the delivery-wheel and operated by a cam fixed in the path of movement of the cutter.

9. In a machine for tipping laces, means for supplying a continuous length of lacing to the machine, a carriage adjustable along the frame of the machine and supporting mechanism for applying a metallic tip to and securing it upon the lacing, and a delivery-wheel carrying near its periphery an automatic clamp for grasping the end of the lacing.

and an automatic cut-off for dividing the tip and severing the lacing.

10. In a machine for tipping laces, means for supplying a continuous length of lacing to the machine, means for holding the lacing extended along the frame of the machine, cam-wheels borne on the main shaft and severally engaging mechanisms for feeding a blank into place upon the lacing, for then feeding it lengthwise along the lacing and then closing it upon and securing it to the lacing, and a delivery-wheel carrying an adjustable clamp adapted to grasp the end of the lacing, and a cut-off device for dividing the tip and severing the lacing.
